UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed February 26, 1925. Serial No. 11,693.

This invention aims to provide an improved separable fastener.

In the drawings, which illustrate two preferred embodiments of my invention:—

5 Figure 1 is a front elevation of the fastener;

Fig. 2 is a section on the line 2—2 of Fig. 1;

Fig. 3 is a rear elevation of the socket;

10 Fig. 4 is an elevational view of the socket casing before attachment to a support;

Fig. 5 is a side elevation of the socket casing shown in Fig. 4;

15 Fig. 6 is a front elevation of the second form of my invention, showing a different form of prong-receiving part from that shown in the first form;

Fig. 7 is a section on the line 7—7 of Fig. 6; and

20 Fig. 8 is a section on the line 8—8 of Fig. 6, illustrating the form that the carrying medium assumes when a stud has been engaged with the socket and showing the freedom of the resilient walls of the socket.

25 Referring to the drawings, I have shown a simple, durable and inexpensive type of snap fastener and two simple forms of prong-receiving clench plates for securing the socket casing to its support without cutting a hole in the support except for the attaching prongs.

30 The fastener illustrated in Figs. 1 through 5 includes a stud member having a head 1, a neck 2 and a base portion 3 secured to a flexible support 4 by a tubular rivet 5 upset within the head 1 of the stud in the usual manner. The fastener also includes a socket having a casing secured to a flexible support as more fully hereinafter described.

35 The socket casing, as illustrated, is pressed from a single piece of metal and presents a peripheral cylindrical wall 6, a second cylindrical wall 7 within the peripheral wall 6, and a third cylindrical wall 8 within the

40 second wall. All of the walls are parallel with and spaced away from each other, as illustrated. The walls 6 and 7 are connected by a web 9 at one end of the casing and the walls 7 and 8 are connected by a web 10 at the opposite end of the casing, as illustrated in Fig. 2. At the free end of the third wall 8, I have provided a reversely bent portion 11, which surrounds a stud-receiving aperture 12 and forms means for engagement with the

55 neck of the stud. The walls 7 and 8 are made resilient to permit passage of the head of the stud through the aperture 12 by dividing them into resilient fingers by a plurality of slots terminating in the web 9, as illustrated in Figs. 2, 3 and 4. These fingers are adapted to expand and contract to permit the head of the stud to pass through the stud-receiving aperture and the expansion and contraction of the fingers is distributed over their 60 entire length and not concentrated at any one point. This construction, therefore, is highly desirable because the socket is more durable and the possibility of the fingers becoming "set" is greatly reduced.

65 While the socket casing may be secured to its flexible support 14 in any suitable manner, I prefer to secure it thereto by a clench plate or cap 15 and a plurality of prongs 16. The prongs 16 extend from the peripheral wall 6 of the casing through the support 14 where they are clenched into engagement 70 with the cap 15 as illustrated.

75 Thus the casing is secured to the support 14 without weakening the fabric, as is the case when a central attaching rivet is passed through a hole in the fabric. The fabric 14 is also maintained in substantially the same plane throughout thereby avoiding unnecessary stretching thereof. As illustrated in Figs. 2, 7 and 8, the fabric 14 is 80 stretched loosely over the resilient portions of the socket, and the cap member is spaced away from the fingers at least the thickness of the cloth, so that there is no gripping of the fabric above the fingers. Thus the fingers may contract and expand without interference from the support 14. The cap member is provided with a central dome 17 to provide a space into which the fabric may be pressed when the stud and socket are engaged, as illustrated in Fig. 2.

85 Figs. 6, 7 and 8 illustrate the second form of cap member 18 in combination with a socket substantially as shown and described in the first preferred embodiment of my invention. This type of clench plate or cap member 18 is pressed into the form of a ring-like portion presenting a central aperture for ornamental effect as well as to provide a recess into which the carrying fabric 14 may 90 be pressed by the head of a stud. The ring-like portion comprises an inwardly bent anvil portion 20 and clench flange 21 for receiving

and upsetting the attaching prongs 16 presented by the socket casing, thereby to secure the socket casing to the support 14.

While I have shown and described two preferred embodiments of my invention, it will be understood that I have done so for purposes of clarification only, my invention being best defined in the appended claims.

Claims:

10. 1. A fastener socket installation including a cap part, a carrying medium and a casing part, said casing part presenting a plurality of parallel concentrically arranged walls of substantially uniform height, some of said walls being divided by a plurality of slits to provide laterally yieldable stud-engaging means arranged about a stud-receiving aperture, the cap part being located on one side of the carrying medium and the casing part on 20 the other, and cooperating attaching means in the form of prongs and prong-clenching means for securing said parts together, the said walls and the said cap part presenting surfaces toward the carrying medium which 25 permit the carrying medium between them to lie in substantially the same plane as the remainder of the carrying medium.

2. A fastener socket comprising, in combination, a one-piece socket casing located at one 30 side of a flexible fabric and presenting beyond the face of the fabric a continuous outer peripheral wall, a second wall within the peripheral wall and a third wall within the second wall, all of said walls being parallel and in the same 35 plane, a plurality of slits extending through the second and third walls to provide resiliency, and a plurality of rounded reversely bent portions presented by said third wall to provide for substantial engagement with the neck of 40 a stud, said reversely bent portions expandible with the second and third walls to permit smooth passage of the head of the stud into and out of engagement with the socket, and means integral with the outer peripheral wall 45 for cooperation with means located at the opposite face of the fabric thereby to secure the casing to the flexible fabric.

3. A fastener socket including a casing located at one side of a flexible support and having a peripheral wall presenting a plurality of attaching prongs for cooperation with an attaching part located on the opposite side of the flexible support for securing said casing to the support in such a manner that the 50 support remains imperforate except where pierced by said prongs, a plurality of resilient stud-receiving fingers bent parallel with the peripheral wall, first in one direction and then in the opposite direction and terminating about a stud-receiving aperture, the parallel portions of each of said fingers being spaced relative to each other and relative to

the peripheral wall to permit free lateral flexing of said fingers over their entire lengths thereby to permit the head of a stud to pass 65 between the free ends of said fingers and reduce to a minimum the possibility of the fingers becoming set.

4. A fastener socket installation including a one-piece casing part, a socket-carrying fabric and a clench plate, the casing part and clench plate being secured to opposite sides of the socket-carrying fabric and the fabric between the clench plate and casing part being substantially undisturbed from its normal plane, a plurality of resilient fingers presented by said casing part, jaw means for engagement with the neck of a stud, means providing a space between said jaw means and the socket-carrying fabric for receiving the head 80 of a stud when engaged with said socket and a wall of sufficient height provided as an integral part of said casing part at its periphery to enclose said fingers and said jaws so that they do not project beyond either edge 85 thereof.

5. A fastener socket installation including a one-piece casing member and a cap member secured to opposite sides of a flexible carrying medium by suitable attaching means 90 formed integral with one of said members, a plurality of concentric walls presented by said casing member, the inner walls being split to provide resilient fingers for receiving the head of a stud therebetween, said 95 cap member and said casing member presenting surfaces adjacent their peripheries between which the carrying medium is gripped while permitting the carrying medium inside the gripped area to lie loosely and 100 continuously over said resilient walls between the cap member and casing member without interfering with expansion and contraction of said resilient fingers.

6. A fastener socket installation including 105 a casing member and an imperforate cap member secured to opposite sides of a flexible carrying medium by a plurality of attaching prongs presented by one of said members, a plurality of concentric walls presented by said casing member, the inner walls being resilient to receive the head of a stud, said cap member and said casing member arranged so that the carrying medium lies loosely over 110 said resilient walls to permit flexing without interference therefrom, and a domed portion providing at the central portion of said cap member to receive a portion of the carrying medium when the head of a stud engages the socket-carrying medium.

In testimony whereof, I have signed my name to this specification.

FRED S. CARR.

CERTIFICATE OF CORRECTION.

Patent No. 1,685,063.

Granted September 18, 1928, to

FRED S. CARR.

It is hereby certified that error appears in the printed specification of the above numbered patent requiring correction as follows: Page 2, line 117, claim 6, after the word "providing" insert the article and word "a space"; and that the said Letters Patent should be read with this correction therein that the same may conform to the record of the case in the Patent Office.

Signed and sealed this 23rd day of October, A. D. 1928.

(Seal)

M. J. Moore,
Acting Commissioner of Patents.
